FIG. 1.

FIG. 2.

FIG. 3.

Inventor

Geo. R. Long.

App. Secy

Attorney

UNITED STATES PATENT OFFICE.

GEORGE R. LONG, OF WATERBURY, CONNECTICUT, ASSIGNOR TO CORDLEY & HAYES, OF NEW YORK, N. Y., A CORPORATION OF NEW YORK.

FAUCET.

Application filed February 13, 1923. Serial No. 618,833.

To all whom it may concern:

Be it known that I, GEORGE R. LONG, residing at Waterbury, county of New Haven, State of Connecticut, and a citizen of the United States, have invented certain new and useful Improvements in Faucets, of which the following is a specification, reference being had to the accompanying drawing, forming a part thereof.

- 10 My invention relates to a push faucet and has for its object to provide a faucet of this type in which the force necessary to open the faucet will be independent of the pressure of the liquid to be drawn off.
- 15 In push faucets of the ordinary type the pressure of the liquid to be drawn off acts at all times against the valve tending to hold it against its seat and to thus keep it closed and in order to open the faucet the valve 20 must be forced inward away from its seat against the pressure of the liquid.

When the liquid is drawn from a tank the pressure of the liquid will vary according to the depth of liquid in the tank and consequently the force necessary to be used in opening the faucet will vary and when the tank is full or nearly full the force required may be more than is desirable particularly where the faucet is to be opened by pressing 30 against it a glass into which the liquid is to be drawn.

By the present invention pressure of the liquid tending to close the valve and to resist its opening is avoided so that the force necessary to unseat the valve and permit the liquid to flow is only such as may be sufficient to overcome the force of the spring by which the valve is closed and the force required is always the same whatever the pressure of liquid may be.

With the objects above indicated and other objects hereinafter explained in view my invention consists in the construction and combination of elements hereinafter described and claimed.

Referring to the drawings:

Fig. 1 is a side view of a push faucet embodying the invention.

Figure 2 is a longitudinal central vertical 50 sectional view.

Figure 3 is a side view of the faucet

equipped with a lever adapted to be operated to open the valve by pressing against it the edge of a glass and

Figure 4 is a detail view of the hollow 55 plug.

In the drawings 1 indicates the outer or forward member of the faucet shell or casting and 2 indicates the rear member the two being secured together by screw threads 60 formed on the forward end 17 of the rear member 2 engaging screw-threads formed on the interior of the cylindrical recess 3 formed in the rear end of the forward member 1.

In the forward end of the front member 1 of the faucet shell is formed a cylindrical recess 4 the bottom of which is formed by a partition 5 which separates this cylindrical recess from the chamber 6 from which leads 70 the discharge spout 7. This partition has, in line with the axis of the cylindrical recess 4, an opening 8 for the valve rod 9.

Between the chamber 6 and the cylindrical recess 3 at the rear end of the front member 75 1 is a partition 10 having through it, in line with the axis of the cylindrical recess 3, an opening 11. On the rear face of this partition surrounding the opening 11 is an annular valve seat 12.

The rear member 2 has a rearward tubular extension 13 adapted to enter the faucet hole of a liquid containing tank having its rear end screwthreaded to receive the usual retaining nut (not shown) on the inside of the 85 tank and having near its forward end a polygonal flange 14 for rotating it, this flange being adapted to serve as an abutment for a disc 15 carrying a washer 16 to bear against the outer surface of the wall of the tank.

Forward of the flange the end 17 is exteriorly screwthreaded in the rear end of the front member 1 and is interiorly screwthreaded at 18 to receive a hollow plug 20 95 open at its forward end and closed at its rear end at its rear portion in rear of the screwthreads 21 for engaging the screwthreads 18, of reduced diameter and provided with openings 22 through its walls.

By reason of the reduced diameter of this rear portion of the plug, an annular passage

23 is left between it and the inner surface of the forward end of the bore of the rear member 2.

The valve rod 9 is provided within the cylindrical recess 3 with a valve 25 and carries on its rear end a solid cylinder 26 adapted to enter the bore of the hollow plug 20 this solid cylinder 26 being so arranged that when the valve rod is in its forward position and the valve 25 against its seat 12 this solid cylinder will be opposite to and will serve to close the openings 22 and when the valve rod is pushed rearward to move the valve 25 away from its seat the forward end of this solid cylinder will be to the rear of the openings 22 and flow of liquid through them from the annular passage 23 will be unobstructed.

An annular washer 27 between the rear end of the front member 1 and the flange 14 of the rear member serves to ensure a liquid tight joint between the two members.

The valve 25 is forced outward against its seat to close the faucet by a spring 30 arranged within the cylindrical recess 4 bearing at one end against a washer 31 which rests against the partition 5 and bearing at the other end against a cap 32 secured on the end of the valve rod 9. Pressure on the head of the cap will force the valve 25 away from its seat and will carry the cylinder 26 inward past the openings 22. On releasing the pressure on the head of the cap the spring 30 forces the cap outward carrying the valve rod 9 to move with it.

In the form of faucet shown in Figures 1 and 2 the cap 32 is intended to be pressed inward by the thumb of the operator and in order to enable the necessary pressure to be applied projections 33 shaped to form finger holds are provided on the side of the faucet member 1. In the form shown in Figure 3 the faucet member 1 is provided on its upper side with a lug 34 in which is pivoted the upper end of a depending lever 35 the lower end of which is in position to be pressed against by a glass 36 into which liquid is to be drawn. About in line with the valve rod 9 a link 37 is pivotally connected with the lever 35 the forward end of this link adapted to bear against the cap 32.

When a glass is held beneath the spout 7 and is pressed rearward against the lower end of the lever 35 to swing it rearward the

link 37 presses the cap inward against the force of the spring 30 and thus opens the faucet.

The valve 25 being an inwardly opening valve the pressure of the liquid in the tank from which it is to be drawn tends to force the valve against its seat and, in the push faucet as ordinarily constructed, the valve has to be opened against this pressure of liquid, the pressure varying with the height of the liquid in the tank. By use of the cylinder 26 the liquid is shut off so that as soon as the valve is closed and the liquid in the chamber 6 has drained off through the discharge spout, there is no pressure of liquid on the valve 25 to resist its opening. The pressure on the cylinder 26 through the opening 22 is radial and does not tend to force the valve rod outward.

Having thus described my invention what I claim is:—

1. In a push faucet a valve rod, an inwardly opening main valve carried by the valve rod, a spring acting on the valve rod to hold the valve to its seat, and a second valve carried by said valve rod in rear of the main valve adapted to cut off pressure of liquid from the tank against the main valve said second valve being so arranged that the pressure of the liquid from the tank acts against it at right angles to the direction of movement of the valve rod.

2. In a push faucet an outer member provided with a discharge spout and having a partition provided with an opening, a valve arranged to bear against the inner face of the partition to close said opening, a valve rod for said valve, a spring arranged to act on the valve rod to hold the valve in closed position, and an inner member adapted to be secured to the outer member, provided with a rearwardly extending tube to enter the faucet hole of a tank and having in its forward end a hollow plug closed at its rear end and having an opening in its walls and a cylindrical piston carried by the valve rod adapted to open and positively close the opening in the walls of the hollow plug without direct resistance by the liquid in the container.

In testimony whereof I hereunto affix my signature.

GEORGE R. LONG.
